(57) **CLAIM**

I claim the ornamental design of a go-kart exhaust with vibration isolation coupler, as shown and described herein.

DESCRIPTION

FIG. 1 is a perspective view of a go-kart exhaust with vibration isolation coupler according to the new design.

FIG. 2 is a side view of the go-kart exhaust with vibration isolation coupler according to the new design.

FIG. 3 is a sectional view of section A of FIG. 2.

FIG. 4 is a top view of the go-kart exhaust with vibration isolation coupler according to the new design; and,

FIG. 5 is a bottom view of the go-kart exhaust with vibration isolation coupler according to the new design.

1 Claim, 5 Drawing Sheets

FIG. 1

FIG. 2

FIG. 3

FIG. 4

FIG. 5
